CLAIM

The ornamental design for a sign holder, as shown and described.

DESCRIPTION

FIG. 1 is a front-top-right view of a sign holder in an exploded configuration showing my new design;

FIG. 2 is a rear-bottom-left view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left elevational view thereof;

FIG. 8 is a right elevational view thereof;

FIG. 9 is a front-top-left perspective view of the sign holder in an assembled configuration;

FIG. 10 is a front-top-left perspective view thereof deployed with a sign; and,

FIG. 11 is a rear-bottom-right perspective view thereof.

The broken lines showing a detachable sign and fastening devices in FIGS. 1 through 11 are included for the purpose of showing environmental structure and form no part of the claimed design.

1 Claim, 11 Drawing Sheets
